SCREEN.

1,308,998.

Specification of Letters Patent.

Patented July 8, 1919.

Application filed April 19, 1918. Serial No. 229,615.

To all whom it may concern:

Be it known that we, AVON L. STONE and JOHN M. STONE, citizens of the United States, residing at Lodi, in the county of San

5 Joaquin and State of California, have invented certain new and useful Improvements in Screens, of which the following is a specification.

This invention relates to grain separators, 10 and more particularly to the separating screens thereof, aiming primarily to provide improvements upon separating screens of the general character illustrated in the patent granted to John M. Stone, October 4th 1910,

15 #971,701.

A further object of the invention is to provide a screen so constructed as to obtain the highest degree of vibration in the wires thereof, whereby the efficiency of screens of

20 this character is greatly increased.

A further object is to provide a screen including a frame of simple construction and possessing great strength, and which is equipped with such improved means for attaching the wires to the ends of the frame as will permit of the various strands of the wire being stretched at equal tension, and which automatically distributes the slack or looseness occurring in any one strand evenly to 25 all of the strands, thus greatly reducing the opportunity for breakage of the wires.

Further objects and advantages will appear hereinafter.

In the drawings:

35 Fig. 1 is a plan view of a screen constructed in accordance with the invention,

Fig. 2 is an enlarged longitudinal sectional view of the screen taken substantially upon line 2—2 of Fig. 1, and

40 Fig. 3 is a transverse sectional view taken upon line 3—3 of Fig. 1.

In carrying out the invention, we provide a frame constituting side and end bars formed preferably of metal, and disposed at right angles to each other. The end members of this frame support the ends of the wire strands which cover the frame, and the bearing surfaces provided by these end members are extremely narrow so as to minimize the 45 area of contact of the wires with the bearing surface, and yet these surfaces are not so narrow as to cut or injure the wires. Each of the end members is provided with a stretching or tensioning rod, and these tensioning rods are rotatably supported and capable of moving parallel with and angu-

larly toward or away from the bearing surfaces. Hook bolts or other suitable securing elements are engaged with the tensioning rods, and are capable of being minutely adjusted so as to control the movement of the rods. The hook bolts or securing elements are constructed in such manner as not to permit of the rods moving into the same plane with the adjacent bearing surfaces, so

60 that the high degree of vibratory action of the strands caused by stretching the same across the restricted bearing surfaces will not be impaired or destroyed. It is preferred that a single wire be used for the 65 screen, and this wire is crossed back and forth across the frame and the bearing surfaces thereof, and around the tightening rods at the ends of the frame. By loosely extending the wire around the tensioning 70 rods, the various strands are capable of adjusting themselves longitudinally of the frame, whereby uniform tension in all of the strands is established and maintained. In

75 order that the various strands may be spaced 80 apart an equal distance throughout the width of the frame and to maintain the strands so positioned, the bearing surfaces at the ends of the frame may be provided with shallow notches to receive the strands.

85 As the frame is formed of metallic bars there is a greater or less amount of resiliency therein, and when the securing elements for the tensioning bars are moved so as to stretch the strands tightly across the 90 frame, the latter is bowed slightly, and the tendency of the frame to straighten or assume normal or relaxed position causes the various strands to possess the requisite tension.

95 Referring now more particularly to the drawings, 5 indicates the longitudinal or side bars of the improved frame, which bars are connected at their extremities by the end bars indicated at 6. The side bars 5 are preferably made of T-iron as shown in Fig. 3, and the upstanding portions of these irons are cut and bent inwardly at their extremities to provide retaining feet 7 to which the end members 6 are connected. The frame 100 also includes a reinforcing or strengthening bar 8, disposed in spaced parallel relation to the side bars 5 and intermediate the longitudinal edges of the frame, being secured at its ends to the end bars 6 as shown.

105 The end members 6 of the frame are formed of L-irons, the base portions of

which are secured by bolts 9 to the bottom portions of the longitudinal members 5—8, while the upstanding portions of the L-irons are bolted as at 10 to the retaining feet 7 of the longitudinal members. By constructing the frame in this manner it is obvious that the latter will be capable of withstanding the strains to which the same will be subjected when the wires are tightened, and 10 such strains are equally distributed to all parts of the frame.

Each of the end bars 6 is provided with means for supporting and tensioning the wires which cover the frame, and this means 15 includes cylindrical tensioning rods 11. These rods are arranged parallel to and slightly beyond the upper edges of the end members 6, and are below the horizontal plane of the said edges. The rods 11 are 20 confined within the hook ends 12 of the bolts 13, the threaded ends of the said bolts being extended through the horizontally disposed portions of the L-irons 6, and the said threaded ends are equipped with nuts 25 14 to enable the said bolts to be adjusted. The portions of the end members 6 through which the bolts 13 extend are bent angularly as shown in Fig. 2 of the drawings, and the bolts 13 are thus capable of moving 30 angularly across the end members. By tightening the nuts 14 the bolts will be drawn downwardly, bringing with them the rods 11, and this downward movement of the rods causes the wires indicated at 15 to be tensioned. When the nuts 14 are loosened, the strain of the wires 15 causes the rods 11 to move upwardly and inwardly, but it will be observed that the hook ends 12 of the bolts will engage the upstanding 40 portions of the members 6 before the rods 11 move into the same horizontal plane with the upper edges of the said L-irons. By so constructing the device, the wire strands 15 are always tensioned between the bearing 45 surfaces on the end bars 6 so that the vibratory action of the strands cannot be impaired.

It is preferred that the bearing surfaces provided by the members 6 be very narrow 50 so that the actual surface contact between the strands and the supporting surface will be small. This bearing surface is provided with a number of grooves of shallow depth, spaced apart the desired distance and in 55 which the wire strand rests. By thus grooving the bearing edges of the end members, the strands will be prevented from moving toward or away from each other and will at all times be maintained in proper spaced 60 parallel relation.

The frame is strung preferably with a single wire, secured at one corner of the frame to the tensioning rod 11 and passes upwardly therefrom and over the adjacent bearing 65 surface to the opposite end of the frame.

The wire is then passed around the tensioning rod at the said end and then back to the opposite end of the frame. The continuous strand is thus woven back and forth across the frame until the latter is entirely 70 covered, and the end of the wire may then be secured to the tensioning rod adjacent which it is disposed. The strands are then tensioned by operating the nuts 14, and by reason of the fact that the strands pass 75 loosely around the tensioning rods and as the latter are rotatably supported within the hook portions 12, an even tension in all of the strands is established and maintained. By this particular arrangement, the 80 various strands are capable of automatically adjusting themselves, whereupon the strain throughout the frame and upon all of the wire strands is equalized, and danger of overstraining some of the wires or breaking of the latter is exceedingly remote. By reason of the fact that the frame is formed of metallic bars, the same will be slightly bowed when the wires are tensioned, and the elasticity in the frame tends to maintain the 85 wire strands at the requisite tension. 90

While the present is a disclosure of the preferred embodiment of the invention, it is to be understood that the invention is not limited thereto, as various changes in the 95 minor details of construction, proportion, and arrangement of parts may be resorted to if desired without departing from the spirit of the invention as defined by the appended claims.

We claim:—

1. In a grain separating screen, a frame having bearing surfaces at each end, hook bolts at the ends of said frame capable of moving angularly toward or away from 105 said surfaces, cylindrical bars loosely enclosed by said hook bolts and disposed parallel with and below the plane of said bearing surfaces, nuts on said bolts for adjusting the latter, and strands covering said 110 frame and resting at their ends upon said surfaces and passed around said bars.

2. In a grain separating screen, a frame having parallel end members formed of angle bars, the ends of the upstanding portions of said bars forming bearing surfaces, retaining elements supported by the other of said portions and capable of moving angularly toward or away from the first mentioned portion, cylindrical rods rotatably 115 carried by said retaining elements and disposed parallel with said bearing surfaces, and strands covering said frame resting at their ends upon said surfaces and engaged around said rods.

3. A grain separating screen comprising a frame having L-irons having their horizontal portions angularly bent, bolts extending through openings formed in the said angularly bent portions, the ends of the 130

said bolts having hooks, wire strands extending between the said L-irons and mounted upon the edges of the vertical portions of the said L-irons, tensioning rods 5 carried by the said hooks and attached to the said wire to tension the wires when the said bolts are adjusted in the said angularly bent portion of the L-irons.

In testimony whereof we affix our signatures in presence of two witnesses.
